UNITED STATES PATENT OFFICE.

NELVILLE JOE ADER, OF PORT ARTHUR, TEXAS.

TROUSERS-POCKET CONSTRUCTION.

Application filed April 19, 1926. Serial No. 103,112.

This invention relates to trousers, more particularly to the pocket constructions thereof, and has for its object to provide, in a manner as hereinafter set forth, a pocket having wall portions thereof formed from inherent parts of the material providing the trouser body thereby producing an unusually strong and durable pocket of a construction to overcome side seam ripping and tearing out thereof.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of one of the front sections of a pair of trousers.

Figure 2 is a like view of one of the rear sections of a pair of trousers and which associates with the section illustrated in Figure 1.

Figure 3 is an elevation looking toward one of the front sections and its associated rear section of a pair of trousers secured together wrong-side out.

Figure 4 is a fragmentary view, in elevation, looking toward one of the rear sections and its associated front section of a pair of trousers secured together wrong side out.

Figure 5 is a fragmentary view, in elevation, looking toward one of the front sections and its associated rear section of a pair of trousers secured together right side out.

Figure 6 is a view similar to Figure 5 looking toward one of the rear sections and its associated front section of a pair of trousers secured together right side out.

Figure 7 is a section on line 7—7, Figure 3.

Figure 8 is a section on line 8—8, Figure 3.

Figure 9 is a section on line 9—9, Figure 4.

Figure 10 is a section on line 10—10, Figure 4.

Figure 11 is a section on line 11—11, Figure 6.

Figure 12 is a fragmentary view, in elevation, of a modified form of trouser section.

Figure 13 is a fragmentary view, in elevation, of the modified form of trouser section shown in Figure 12 and with the pocket wall folded.

Figure 14 is a section on line 14—14, Figure 13.

Figure 15 is a fragmentary view, in elevation, of still another modified form of trouser section.

Figure 16 is a fragmentary view in full and dotted lines, the full lines indicating the other trouser section associated with the section shown in Figure 15, the dotted lines indicating the trouser section shown in Figure 15 positioned with respect to its associated section.

Figure 17 is a fragmentary view in elevation, of the forms of trouser sections shown in Figures 15 and 16 secured together and turned right side out.

Figure 18 is a section on line 18—18, Figure 17.

Referring to Figures 1 to 11 of the drawings 1 indicates one of the front sections and 2 indicates one of the rear or back sections of a pair of trousers. The sections 1 and 2 associate and are secured together to provide one-half of the trousers, that is to say one of the legs and one-half of the body portion of the trousers.

The section 1 has projecting from its outer edge, in proximity to its top, an integral flap 3 which is formed of the same material as that of said section and further which provides one of the walls of a side pocket of the trousers. The flap 3 is angularly disposed with respect to the section 1, that is to say it extends upwardly at an inclination and includes an upwardly extending inclined top edge 4, an outwardly extending inclined outer edge 5 and a downwardly curved lower edge 6 of greater length than the top edge 4. The flap 3 gradually increases in length from its upper to its lower portion. The section 1 is furthermore provided at its top with a pair of spaced slits 7, 8 and the lower terminal of each of said slits is inclined as at 9. The inclined portions are oppositely disposed and extend away from each other.

The section 2 has projecting from its outer

edge, in proximity to its top, an integral flap 10 formed of the same material from which the section 2 is constructed, and the said flap 10 forms the other wall of the side 5 pocket of the trousers. The flap 10 associates with the flap 3 to provide the side pocket. The flap 10 is angularly disposed with respect to the section 2 and includes an upwardly extending inclined top edge 11, an 10 outwardly inclined outer edge 12, and a downwardly curved bottom edge 13 of greater length than the top edge 11. The flap 10 gradually increases in width from its upper to its lower portion. The top of 15 the section 2 is furthermore provided with a pair of spaced slits 14, 15 of greater length than the slits 7 and 8 and the inner terminal of each slit 14, 15, is inclined as at 16 and the said inclined portions are oppositely disposed with respect to each other and project 20 away from each other.

The material freed by the slits 7 and 8 is indicated at 17, it extends above the top edge of section 1, provides a flap and which 25 is employed to set up the watch pocket of the trousers arranged at the waist thereof. The material freed by the slits 14, 15 is indicated at 18; it extends above the top edge 30 of section 2, provides a flap and which is employed in connection with the setting up of the back or hip pocket of the trousers.

The sections 1 and 2 are secured together wrong side out, see Figure 3. Prior to the securing of the sections 1 and 2, wrong side 35 out, the section 1 is positioned upon the section 2, so that the flap 3 will be arranged in superposed relation with respect to the flap 10. A row of stitching 19 is employed for securing the sections 1 and 2, wrong side out, and said stitching is positioned in proximity 40 to the outer edges of the sections 1 and 2, extends from the bottom of said sections, to the point of joinder of the bottom edges of the flaps with the side edges of the sections, then 45 completely around the flaps in proximity to the free edges thereof to the point of joinder of the flaps with the side edges thereof and from such point of joinder extends to the top edges of the sections, see Figure 3.

50 Before the sections 1 and 2 are secured together, in the manner as referred to, the watch and hip pockets are formed. With respect to the manner of setting up the watch pocket the material 17, freed by the slits 7 and 8, is folded against the inner face of the section 1, as indicated in Figure 7. A facing 19' is then secured to the fold 17 and said facing 19' projects above the bend 20 an appropriate distance. The facing 19' is of 55 slightly greater width than the fold 17 so as to overlap the edges of the slits 7 and 8 and said facing 19' is secured in proximity to its edges, as indicated at 21, to the fold 17 and is also secured to the section 1 as indicated at 60 22. When the waist band 23 is secured in

position, that is to say at the top of the section 1 it forms the top edge of the mouth 24 of the watch pocket, see Figure 5.

With respect to setting up the back or hip pocket a rectangular piece of fabric indicated at 25 is secured to the section 2 and is formed with a pair of slits which align with the slits 14 and 15. The strip of fabric 25 is flushed at its top edge with the top edge of the section 2 and depends below the bottom of the slits 14 and 15. The slits formed in the piece of fabric 25 terminate adjacent the inner edge thereof. The material freed by the slits formed in the piece of fabric 25 is indicated at 26. The freed material 26 is 70 bent downwardly, see Figure 9, and the material 18, freed by the slits 15 and 16 is also bent downwardly, see Figure 9. A facing strip 27 is secured at its lower end, as at 28 to the free ends of the freed material 18 and 26, see Figure 9. The facing strip 27 has its lower portion 28 of less width than its upper portion 29. The means for securing the lower end of the facing strip 27, to the free ends of the freed material 18 and 26, as 75 indicated at 28', is a row of stitching and which extends throughout each side and the bottom of the facing strip 27 and not only secures the latter to the freed material 18 and 26, but also secures the facing strip 27 to the section 2. See Figures 4, 9 and 10. The facing strip 27 is of the same material 80 from which the section 2 is constructed and projects above the mouth 30 of the hip or back pocket, see Figure 6, and is enclosed at 85 its top, by the waist band 23.

When the sections 1 and 2, as well as the flaps 3 and 10, are secured together by the row of stitching 19, the sections 1 and 2 are turned right side out and the folds 3 and 10 bent inwardly to assume the dotted line 90 position shown in Figures 5 and 6 and which will provide a side pocket. The flaps 3 and 10 when turned right side out will be positioned in the manner as shown in 95 Figure 11.

Referring to Figures 12, 13 and 14 of the drawings, 31 indicates one of the front sections of the trousers and which is formed to provide one of the walls of what may 100 be termed a top or front pocket. The section 31 at its top is provided with an angularly disposed flap 32 and which is disposed at an inclination and set up with an outwardly inclined edge 33 and a curved edge 105 34. The edge 33 extends from the top edge of the section 31 and the edge 34 extends from the outer side edge of the section 31 in proximity to its top. The flap 32 is folded upon an inclination as indicated at 110 35. Secured to the flap 32 is a facing 36 which extends above the bend 35 and forms a continuation of the top and outer side edges of the section 31, see Figure 13. The mouth of the pocket is indicated at 37 and 115 38.

is arranged below the top edge of the section 31. The facing 36 is of the same material from which the section 1 is formed. One side edge of the facing 36 is secured throughout to one side edge of the flap 32 and the other side edge of the flap 32 is secured throughout to a portion of the other side edge of the facing 36.

Referring to Figures 15, 16, 17 and 18 of the drawings a modified form of pocket is set up and which has its mouth disposed at an inclination and out of alignment with the outer seam of the leg of the trousers. The reference characters 38 and 39 indicate respectively one of the front sections and one of the rear or back sections of the trousers. The section 38 associates with the section 39 to form one of the trousers legs and half of the body of the trousers. The section 38 has extending from the upper outer corner thereof an inclined flap 40 formed with an outwardly inclined upper end edge 41, a downwardly inclined top edge 42 and a curved lower end edge 43. The edge 41 terminates in the top edge of the section 38 and the edge 43 terminates in the outer side edge of the section 38. The flap 40 is folded upon an inclination against the section 38, and the point of the bend of the fold is indicated at 44. The flap 40 is formed of the same material from which the section 38 is set up. The section 39 has projecting outwardly therefrom, at its upper end, a flap 45 which at its upper portion is of materially greater width than the flap 40 and the flap 45 is bent inwardly upon the point indicated at 46. When the sections 38 and 39 are connected together, the flap 40 is positioned upon the flap 45 as shown in Figure 16 and said flap 40 has its edges 41, 42 and 43 secured to the edges 47, 48 and 49 of the flap 45. When the flaps are

secured together a triangular portion of the flap 45 is disconnected from the flap 40, see Figure 16 and when the sections 38 and 39 are turned right side out and the pocket formed by the flaps 40 and 45 arranged between the trousers sections, the triangular shaped portion, which is indicated at 50 projects from the mouth 51 of the pocket. See Figure 17.

It is thought that the many advantages of a pocket construction for trousers, in accordance with this invention, can be readily understood, and although the preferred embodiments of the pockets, in accordance with this invention, are as illustrated and described, yet it is to be understood that changes in the details of construction can be had which will fall within the scope of the invention as claimed.

What I claim is:—

1. In pocket construction for trousers, a trousers section having an inturned inherent portion providing from its point of joinder with the body of the trousers section to its free edge throughout one complete side wall of the pocket, and means opposing and secured to said inturned portion throughout the free edge of the latter to provide the other complete side wall of the pocket, said inturned portion arranged at the upper part of said trousers section.

2. In pocket construction for trousers a trouser section provided with an inherent inturned flap forming one complete side wall of the pocket, and a trouser section formed with an inherent inturned flap providing the other complete side wall of the pocket, and means for securing said flaps together in proximity to the edges thereof.

In testimony whereof, I affix my signature hereto.

NELVILLE JOE ADER.
